UNITED STATES PATENT OFFICE.

FREDERICK S. FOLTZ, OF THE UNITED STATES ARMY.

RAILROAD-JOINT.

SPECIFICATION forming part of Letters Patent No. 430,939, dated June 24, 1890.

Application filed June 12, 1889. Serial No. 314,050. (No model.)

To all whom it may concern:

Be it known that I, FREDERICK S. FOLTZ, a citizen of the United States, and a lieutenant in the First Regiment of Cavalry of the 5 United States Army, stationed at Fort Assiniboin, Territory of Montana, have invented certain Improvements in Railroad-Rail Joints, of which the following is a specification.

My invention relates to that class of rail-joints in which tongues on the ends of adjoining rails lap each other horizontally; and the object of my invention is to so construct a good rigid joint that the wheels of the rolling-stock will obtain a firm tread upon the 15 end of each rail before leaving the preceding one or the joint, in order to prevent the jar and racket occasioned by the wheels striking the full end of one rail when they leave the other, as they now do with joints as generally 20 made.

Another object of my invention is to so shape the tongues of the joints as to render them cheaper and more easy of construction than other lapping joints in use.

The invention consists in making the longitudinal cuts for forming the recesses in diagonal planes passing through the centers, or thereabout, of the tops of the rails and a line lying in the horizontal plane of the bases 30 thereof.

In the accompanying drawings, which form part of this specification, Figure 1 is a perspective view of the end of one of the rails, and Fig. 2 a similar view of the end of the adjoining rail, which laps it. Fig. 3 is an end elevation of the same, and Fig. 4 a similar view of the contiguous end of the adjoining rail. Fig. 5 shows a side elevation of my 35 joint, and Fig. 6 a top or plan view of the same.

A and B represent the ends of two adjoining rails, connected in the usual manner by fish-plates D and bolts and nuts, as shown in Fig. 5. The ends of the heads of these rails 45 are constructed to lap each other horizontally. In one A the head, web, and base terminate in the same vertical plane, and a recess c is cut in the side of the head at the end. In the other B a tongue formed from a portion of the head projects beyond the web and base a

distance equal to the length of the recess C, the tongue being formed from one side of the head of the rail, thus leaving a recess in the opposite side thereof. These recesses in the ends of the rails form corresponding tongues 55 a and b, which, when the rails are brought together end to end, engage therewith and make a lap-joint, as seen in Figs. 5 and 6.

To facilitate the cutting out of the recess in the rail A, the side c is made in a diagonal plane, passing through the center of the top of the head of the rail and a line lying in the horizontal plane of its base and parallel therewith, as shown by the dotted lines x in Fig. 3, and the side d of the recess in the rail B is made 60 to conform with the side c. Cutting the sides of the recesses in the manner described prevents the saw used for that purpose and for cutting the ends thereof from being brought into contact with either the web or base of 65 the rails. The plane of the inner ends of the recesses is made at right angles with the vertical longitudinal plane of the axis of the rails. Cutting the inner side of the recess of the rail A, so that it inclines or slopes outward from the top of the head of the rail toward the bottom thereof, also forms a bearing 70 for the tongue b of the rail B.

If desirable, as forming a better and firmer locking-joint, a recess may be cut in both the 75 head and base of the rail A, and the head and base of the rail B be provided with a tongue. The manner in which the rails would be cut in this case is shown by the dotted lines z y, 80 Figs. 1, 3, and 4.

To prevent any possible jarring as the wheels of the rolling-stock strike the ends of the tongues a and b, the ends of those tongues are slightly beveled, as shown at f.

It will be seen that by constructing my 85 rail-joint as just described not only does the end of one rail receive the weight of each wheel before it has left the end of the other, but that the lapping of the tongues a and b afford lateral support to each other and give 90 stiffness and rigidity to the joint.

I am aware that prior to my invention railroad-rail joints have been made in which the ends of the rails were constructed to lap each other in such manner as to afford mutual sup- 95 100

port to avoid the use of fish-plates and similar connections. I therefore do not claim the lapping of the joints, broadly; but

What I do claim as my invention, and desire 5 to secure by Letters Patent, is—

1. In a railroad-rail joint, the combination, with a rail having the head, web, and base terminating in the same vertical plane and having a recess cut in the side of the head, 10 of rail having a tongue formed from a portion of the head and projecting beyond the web and base and forming a recess in the side of said head, the side of the recess running lengthwise of each rail lying in a plane, passing through the center of the top of the head thereof, and a line lying outside of its base and parallel therewith, substantially as and for the purpose specified.

2. In a railroad-rail joint, the combination, 15 with a rail having the head, web, and base terminating in the same vertical plane and having a recess cut in the side of the head,

of a rail having a tongue formed from a portion of the head and projecting beyond the web and base and forming a recess in the side 25 of said head, the side of each recess lying in a plane passing through the upper surface of the rail and a line in the horizontal plane of the base, but outside of the same, substantially as and for the purpose specified.

3. A railroad-rail joint made by constructing tongues upon the opposite sides of the contiguous ends of the rails, so as to form recesses, each adapted to receive the tongue of the contiguous rail, the longitudinal interior 35 faces of said tongues lying in a plane passing through the heads of said rails and diagonally downward to and through the plane of the bases of the same, substantially as and for the purpose specified.
